(57) **CLAIM**

The ornamental design for a puzzle as shown and described.

DESCRIPTION

FIG. 1 is a front plan view of the puzzle, according to the present invention;

FIG. 2 is a rear plan view of the puzzle;

FIG. 3 is a front, right side perspective view of the puzzle; and,

FIG. 4 is a front, left side perspective view of the puzzle. The broken lines that illustrate the text "CHARLIE" on the puzzle form no part of the claimed design. The equally spaced broken lines on the interior perimeter of the circle, square, triangle, hexagon, and star shapes of the puzzle illustrate surface ornamentation and form part of the claimed design.

1 Claim, 1 Drawing Sheet
